UNITED STATES PATENT OFFICE.

NOBORU TERASHIMA, OF SHINNAKADORI, JAPAN.

SHUTTLE.

1,081,169.

Specification of Letters Patent.

Patented Dec. 9, 1913.

Application filed December 16, 1911. Serial No. 666,303.

To all whom it may concern:

Be it known that I, NOBORU TERASHIMA, a subject of the Emperor of Japan, residing at No. 13 Shicho-me, Shinnakadori, Wa-
5 kayama-shi, Japan, have invented certain new and useful Improvements in Shuttles, of which the following is a specification.

My invention relates to weaving and consists of an improved form of shuttle and
10 means for operating the same.

One object of my invention is to weave weighty and slippery wefts such as rushes, strips of bamboo, wire, or the like and to keep the ends of the said wefts even.

15 Another object is to facilitate and cheapen the cost of the production of fabrics having wefts of the above described type.

These objects I attain in the following manner reference being had to the accompanying drawings in which:

Figure 1 is a plan view of my improved shuttle; and Fig. 2 is a longitudinal sectional view thereof.

As shown in Fig. 2, the board (A), with
25 a plane surface, and the board (B), with a convexed surface, form the body portion of the shuttle and are so engaged by the bolt (C) in their middle portion, that the both ends of the board (B), of which the elevated
30 part acts as a fulcrum, may alternately rise up and fall down to make an opening or closing jaw at each end of the said body portion, and the boards (A) and (B) are made a little narrower in their breadth to-
35 ward their ends, and in the inside portion near the end, a piece (D) of india-rubber or some other means of adding to friction is provided. Stop pieces E made of a soft material such as leather, are attached to the
40 respective adjacent surfaces of the boards A and B at predetermined distances from both ends. The board B is grooved longitudinally along the middle of the lower surface and this groove forms a guideway for
45 a slider G. The slider is enlarged at each end to form shoulders H, H; the latter projecting outwardly from the narrow portions of the boards A and B. The slider G is provided at each end with antifriction roll-
50 ers I, I adapted to engage oppositely inclined grooves or cams in the portion or portions of either one or both of the boards A and B. So that if the slider G is held station-
55 and forth, the cams will engage the respective antifriction rollers and the board B will

rock to alternately move each end toward and away from the board A. The slider (G) may be modified of course, in its construction as the case requires.

In the operation of my invention, the shuttle occupies a position within the shuttle box and a weft is clamped between two adjacent ends of the boards A, B, while the opposite ends of the said boards are separated as clearly shown in Fig. 2. In this position, the antifriction rollers adjacent the said clamped end are against the low portions of their respective cams and the antifriction rollers which are adjacent the open end of the shuttle are in engagement with the high portions of their respective cams.

As previously stated my invention is best adapted for the weaving of such straight, weighty and slippery weft-threads as rushes, pieces of bamboo and wire, therefore when the shuttle is moved by the picker out of the said shuttle box and across the shuttle race, the weft thread will be carried by the closed end of the body portion until the forward projection H strikes one of two checking devices or stops. The inertia of the body portion will then cause the high portion of the cams which are adjacent the closed ends of the shuttle to engage their respective antifriction rollers I, and thereby tend to separate the boards A and B at this end to release the weft just carried thereby and to close the opposite end of the shuttle to clasp another weft which is to be carried in the opposite direction across the loom. The shuttle is then picked again across the loom and carries the said latter weft thread therewith until the shoulders H on the opposite end of the slider G contacts with the said second stop and the inertia of the body portion causes the high portions of the cams adjacent the closed end to engage their respective antifriction rollers and thereby separate the boards A and B at this end to release the weft thread just carried and to close the opposite end to clamp another weft to be carried across the loom in the opposite direction in a manner previously described.

The stop pieces E serve, when the shuttle has stopped within a shuttle box, to prevent the weft being carried over too far by its own inertia as the said stop members form abutments (as shown in Fig. 2) against which the end of the weft strikes. It will thus be seen that, as the stop pieces E can be

placed at any desired distances from the ends of the shuttle, a fabric woven by the use of my invention will have the ends of the wefts even or in alinement. This latter feature renders my invention especially adaptable for making blinds, bamboo-strip screens or roller-screens in which the strips or reeds are of equal length and should have their ends in straight alinement. However, the stop pieces E may be dispensed with if it is so desired.

Having thus described my invention, what I claim as new and desire to secure by Letters Patent is:—

- 15 1. A shuttle for looms comprising a base section; a weft-gripping member pivoted to the base section; and an actuating member for the weft-gripping member movable independently of the base section, said actuating member having a portion arranged to strike and be arrested by a stop on the loom during the passage of the shuttle across the shuttle race, said actuating member having a portion adapted to move the weft-gripping member after the actuating member has been arrested by the stop.
- 20 2. A shuttle for a loom, comprising a base section; a gripping section rockably secured to the base section; and a longitudinally movable actuating member for moving each end of the gripping section toward and away from the base section to respectively grip and release a weft; said actuating member having a projection at each end arranged to strike a stop adjacent each end of the shuttle race, whereby the movement of the body of the shuttle will cause the jaws to be actuated to receive a weft at one end and to release a weft at the opposite end.
- 25 3. The combination in a shuttle for looms, of a body portion having two sections rockably secured together; an actuating member slideable within the body portion; cams formed within the body portion and adjacent each end; and cam-engaging means carried by the actuating member, said member being placed to strike stops adjacent the shuttle race prior to the stopping of the said body portion, said cams alternately engag-

ing the said latter means and thereby alternately separating respective adjacent ends of the sections and simultaneously moving together opposite ends of the sections.

4. The combination in a shuttle for looms of a body portion having two sections rockably secured together; an actuating member slideable within the body portion; anti-friction rollers adjacent each end of the actuating member; and cams formed adjacent each end of the body portion; said actuating member being placed to strike stops adjacent the shuttle race prior to the stopping of the said body portion, said cams alternately engaging adjacent anti-friction rollers and thereby alternately separating respective adjacent ends of the sections and simultaneously moving together opposite ends of the sections.

5. A shuttle for looms comprising a base section; a weft-gripping section mounted on the base section; an actuating member for the weft-gripping section; weft stops interposed between the weft-gripping section and arranged one adjacent each end of the weft-gripping section; and frictional weft-gripping means adjacent each end of the base and the weft-gripping sections.

6. A shuttle for looms comprising a base section; a weft-gripping section mounted on the base section; an actuating member for the weft-gripping section; and a weft stop interposed between the base section and the weft-gripping section so as to be abutted by the weft.

7. A shuttle for looms comprising a base section; a weft-gripping section mounted on the base section; an actuating member for the weft-gripping section; and a weft stop thereon acting as an alining member for the ends of the weft's.

In testimony whereof, I have signed my name to this specification, in the presence of two subscribing witnesses.

NOBORU TERASHIMA.
